F. J. SCHOLZ,
SINGLE DELIVERY MATCH BOX.
APPLICATION FILED FEB. 14, 1918.

1,350,886.

Patented Aug. 24, 1920.

UNITED STATES PATENT OFFICE.

FRANK JOSEPH SCHOLZ, OF HELENA, MONTANA, ASSIGNOR OF ONE-HALF TO
RAYMOND WENDEL SCHOLZ, OF HELENA, MONTANA.

SINGLE-DELIVERY MATCH-BOX.

1,350,886.

Specification of Letters Patent. Patented Aug. 24, 1920.

Application filed February 14, 1918. Serial No. 217,118.

To all whom it may concern:

Be it known that I, FRANK JOSEPH SCHOLZ, a citizen of the United States, residing at Helena, in the county of Lewis and Clark and State of Montana, have invented certain useful Improvements in Single-Delivery Match-Boxes, of which the following is a specification, reference being had therein to the accompanying drawing.

10 The present invention has reference generally to improvements in that class of inventions known as special receptacles and packages and more particularly relates to a single delivery match box.

15 As the primary aim and object this invention resides in the provision of a match box wherein the matches contained therein may be readily and quickly ejected one at a time upon the actuation of the delivering or

20 ejecting means.

It is an equally important object of this invention to provide a match box of such a nature that the matches will be always held in a position to be ejected and will thus co-operate with the ejecting means to assure of an effective operation of the latter.

25 More particularly the present invention embraces the provision of a match box of such a construction that it can be readily re-filled and at the same time is so constructed that the matches therein may be properly adjusted without necessitating the opening of the box.

30 Among the other aims and objects of this invention may be recited the provision of a device of the above character with a view to compactness, and in which the number of parts are few, the construction simple, the cost of production low and the efficiency high.

35 Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a 40 convenient and satisfactory embodiment of the invention. It is to be noted in this connection that minor changes in the construction and arrangement of parts may be made without departing from the principle 45 of operation of the various parts.

The invention is clearly illustrated in the accompanying drawings, in which:

Figure 1 is a perspective of the device in a closed position;

Fig. 2 is a longitudinal section thereof; 60

Fig. 3 is a transverse section taken on line 3—3 of Fig. 2;

Fig. 4 is a front elevation of the invention;

Fig. 5 is a horizontal section taken on line 5—5 of Fig. 2. 65

Similar characters of reference are employed in all the above described views to indicate corresponding parts.

Referring now, more particularly, to the accompanying drawings, there is provided 70 a match box the body 1 of which is rectangular in configuration and consists of spaced end walls 2 connected by a bottom 3 and a top 4. A longitudinal partition 5 is connected to the end walls and to the bottom and top dividing the body of the receptacle into two compartments 6 while doors 7 constituting side walls of the body are pivotally connected to one of the end walls as indicated by the numeral 8 and are removable 75 held in a closed position by latches 9.

With a view toward providing the improved ejecting means one of the end walls is provided with a pair of vertically arranged openings 10 while opposed flanges 85 11 are mounted on the inner surface of the end wall on opposite sides of each opening and serve as guides for the ejecting slides 12. Each of these ejecting slides consists of a plate-like body of a rectangular configuration slidably mounted in the flanged guides 11 for removably closing the opening while bars 13 are carried by the inner surfaces of the plates and vertically thereof and provided with match engaging teeth 14 90 95 which are inclined toward the body of the box so that when one plate is moved upwardly through the instrumentality of thumb pieces carried by the outer surface and adjacent the lower end thereof the teeth 100 are designed for engagement with the stem of the match in a manner that will become apparent so as to move the match upwardly and pass it through one of the ejecting openings 16 formed in the top of the box 105 adjacent said side wall.

As intimated, improved means have been provided for co-operating with the ejecting means to assure of the position of a match at all times adjacent the ejecting slide. In 110

reducing this feature of the invention to practice a follower plate 17 is mounted in each compartment and is controlled by expansion coil springs 18 the respective ends 5 of which are secured to one end wall of the receptacle and adjacent the base of the adjacent follower plate for holding the follower plate at all times in yielding engagement with matches 19, preferably disposed 10 alternately in each compartment as indicated. As is apparent, the outermost match is at all times yieldingly held against the toothed bars 13 so that upon upward movement of one of these bars the match will be 15 projected through the ejecting openings 16. The matches of course are placed in the compartment through the instrumentality of the adjacent door.

In the event that any of the matches 20 become clogged, in order to examine the interior of the compartment without opening the doors, openings 20 are provided in the top for communication with both compartments being removably closed by slides 21.

25 In view of the foregoing description it is thought that a further detailed description of the operation of the invention is entirely unnecessary. Likewise it is believed that the advantages of the invention will be readily 30 apparent.

As many changes could be made in the above construction and many apparently widely different embodiments of this invention could be made without departing from 35 the scope of the invention, and it is intended that all matter contained in the above description or shown in the accompanying drawings shall be interpreted as 40 illustrative and not in a limited sense. It is also to be understood that the language

used in the following claim is intended to cover all the generic and specific features of the invention herein described, and all statements of the scope of the invention, which as a matter of language, might be 45 said to fall therebetween.

Having thus fully described this invention, what is claimed as new and desired to be secured by Letters Patent, is:—

A match box comprising a rectangular body the top of which is provided with an exit opening and with a rectangular opening, the front wall being provided with a rectangular opening, a swingingly mounted door serving as one side wall of the body, 50 so that matches in bulk may be placed therein, a latch carried by the door for holding the same in closed position, a follower plate carried within the body, springs compressed between the follower plate and the rear wall of the body, the follower plate bearing upon matches placed in the body and forcing them toward the forward end where the foremost match is in position to be ejected through the exit opening in the top of the 55 body, flanged guides formed on the inner surface of the front wall adjacent the rectangular opening therein, an ejecting plate mounted in the flanged guides and comprising a plate-like body, a serrated match engaging bar and a finger piece which projects through the said rectangular opening, whereby the raising of the ejecting plate may effect the ejection of a match through the exit opening, and a slide closing the rectangular opening in the top for the purpose 70 specified.

In testimony whereof I affix my signature.

FRANK JOSEPH SCHOLZ.
